[57] CLAIM

The ornamental design for a toy rifle, as shown and described.

DESCRIPTION

FIG. 1 is a front elevational view of a toy rifle showing my new design, the side opposite being a mirror image;

FIG. 2 is a top plan view thereof;

FIG. 3 is an end elevational view thereof;

FIG. 4 is an end elevational view of the end opposite that shown in FIG. 3; and

FIG. 5 is a bottom plan view thereof.

FIG. 2

FIG. 5

FIG. 4

FIG. 3
